US00D889491S

(12) **United States Design Patent** (10) Patent No.: **US D889,491 S**
Yao et al. (45) Date of Patent: ** Jul. 7, 2020

(54) **DISPLAY SCREEN OR A PORTION THEREOF WITH GRAPHICAL USER INTERFACE**

(71) Applicant: **LENOVO (BEIJING) CO., LTD.**, Beijing (CN)

(72) Inventors: **Cen Yao**, Beijing (CN); **Yucheng Jin**, Beijing (CN)

(73) Assignee: **Lenovo (Beijing) Co., Ltd.**, Beijing (CN)

(**) Term: **15 Years**

(21) Appl. No.: **29/616,326**

(22) Filed: **Sep. 5, 2017**

(30) **Foreign Application Priority Data**

Jul. 19, 2017 (CN) 2017 3 0321189

(51) LOC (12) Cl. **14-04**

(52) U.S. Cl.

USPC **D14/486**; D14/489

(58) **Field of Classification Search**

USPC D14/485-495; D20/10, 11, 22-33, 39,

D20/40; D5/20, 26, 30, 40, 63-65

CPC G06F 3/048-04897; G02B 1/00; H04M

(57) **CLAIM**

The ornamental design for a display screen or a portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

The sole FIGURE is a front view of a display screen or a portion thereof with graphical user interface.

The outermost broken-line rectangle illustrates the perimeter of a display screen or portion thereof and forms no part of the claimed design.
